FASTENING DEVICE

Charles H. Pfaffko, Lymansville, R. I.

Application January 11, 1950, Serial No. 137,939

1 Claim. (Cl. 160—349)

1

This invention relates to a fastening device, particularly a fastening device for holding the tie backs of curtains, draperies, and the like to the sides of the window casing.

The usual curtain tie back is fastened in position by tacking the same at the edge of the window casing by means of a small nail or so called tie back pin which has an enlarged decorative head thereon. This manner of securing the tie backs to the window casing is objectionable because each time a curtain is rehung a new hole is invariably made in the said casing. In time this said edge portion of the casing is filled with these small holes.

The general object of this invention is to provide a fastening device of a construction such as to secure a curtain tie back in place without marring the window casing.

A more specific object of this invention is to provide an anchor for a tie back pin of the above character which may be adjustable lengthwise of the window casing and readily secured in place.

Another object of this invention is to provide a bracket to which an anchor for the tie back pin may be adjustably secured.

With these and other objects in view, the invention consists of certain novel features of construction, as will be more fully described and particularly pointed out in the appended claim.

In the accompanying drawings:

Figure 1 is a perspective view of a fragmental portion of a window casing showing a curtain hung thereon with a tie back secured in position by a fastening device embodying my invention;

Figure 2 is a perspective view of the rear side of the fastening device shown in Figure 1 on an enlarged scale;

Figure 3 is a perspective view of the fastening device shown in Figure 1 on an enlarged scale and turned end on end to show its position when applied to the other side edge of the window casing;

Figure 4 is a perspective exploded view of the anchoring means for the tie back pin;

Figure 5 is a sectional view taken substantially along line 5—5 of Figure 1;

Figure 6 is a view of a modified bracket;

Figure 7 is a perspective view of a still further modification of the invention.

Referring to the drawings for a more detailed description of the invention, 10 designates generally a window casing from which there is hung a curtain 11, such as by means of a curtain rod 12. The curtain 11 is provided with a tie back 13 which consists of a strip of fabric formed into a

2

loop 14 (see Fig. 5) through which is passed the lower portion of the curtain 11. The tie back 13 is brought adjacent to the edge of the side 15 of the casing 10 and is there secured to hold the upper portion of the curtain in a draped manner.

In accordance with the preferred form of the invention, I provide a bracket designated generally 16 having integral right angularly arranged sides 17 and 18. The side 17 is provided with mounting openings 19 at the end portions thereof and the side 18 has an elongated opening or slot 20 extending lengthwise of the said side 18. A pair of brackets 16 is provided for each window casing 10 and these are positioned opposite each other at the sides of the casing with the side 17 in abutting relation with the edge 21 and in a manner such that the side 18 extends outwardly from this edge 21 to be substantially flush with the surface of the face of the casing. The bracket may be attached in position in any appropriate manner such, for example, as by means of screws 22 extending through the openings 19 and into the edge 21.

25 An anchor member designated generally 23 (see Figures 4 and 5) has an externally threaded shank 24 and is provided with a central threaded opening 25 and an enlarged head 26 non-circular in cross section. The member 23 is attached to the side 18 of the bracket by passing the shank 24 through the slot 20 with the head 26 thereof engaging the rear surface of said side 18 (see Fig. 2). A knurled circular nut 27 engages the shank 24 to adjustably secure the said member 23 to the side 18. The head 26, as previously stated, is non-circular in cross section and is of a size to engage the adjacent surface of the side 17 (see Fig. 5) which prevents rotation of the anchor member 23 so as to facilitate the manual turning of the said nut 27 without the use of tools.

The free ends of the tie back 13 are attached to the member 23 by means of a headed pin 28 which has a sharp pointed threaded shank 29 (see Figure 4) which passes through the said free end portion of the tie back ends between the anchor 23 and the head 30 of the tie back pin 28. The head 30 may be of any decorative shape.

50 The bracket 16 may be made of any suitable material such as sheet stock blanked and bent into proper shape or the same may be molded from appropriate materials, such for example, synthetic plastic materials. In some instances, the bracket may be shaped as shown in Figure 6 wherein, the side 17 is omitted and pierced ears

31 are provided at the end portions of the said side 18 for attaching the bracket to the window casing 10.

In Figure 7 I have shown a modified construction of a bracket which is particularly adapted to be attached to the front surface of the sides of the window casing. The bracket comprises a body 44 having a flange 45 extending inwardly thereof and a slot 46 extending lengthwise of the said body 44. The said body is also provided with attaching ears 47 at each end thereof and which ears are provided with an opening 48 for receiving a screw 49 for attaching the said bracket to the window casing. The anchor 23 is mounted on the bracket 44 in a manner similar to that above described by passing the shank 24 thereof through the said slot 46 and securing the same in place by means of the nut 27.

It will now be apparent that I have shown a device which is particularly adapted for providing an anchor for the tie backs of curtains which is sufficiently simple to be readily permanently attached in position on the window casing and to which the said tie back may be anchored.

I claim:

A curtain tie-back device comprising a bracket

4 having a longitudinal slot therein, a member having a threaded portion extending through said slot and provided with a threaded opening therein, threaded means for engaging said threaded portion for securing said member in adjusted position on said bracket, a tie-back strap adapted to be formed into a loop for enclosing the curtain to be tied back, and a pin member having a pointed end adapted to pierce 5 said strap and a threaded shank for engaging said opening for securing said strap to said member.

CHARLES H. PFAFFKO.
